United States Patent Office.

WILLIAM F. PATTERSON, OF CHARLESTOWN, MASSACHUSETTS.

Letters Patent No. 66,250, dated July 2, 1867.

IMPROVED EXPANDING REAMER.

The Schedule referred to in these Letters Patent and making part of the same.

TO ALL WHOM IT MAY CONCERN:

Be it known that I, WILLIAM F. PATTERSON, of the city of Charlestown, in the county of Middlesex, and State of Massachusetts, have invented a new tool for enlarging, smoothing, and truing holes in metals, designated an Expansive Reamer; and I do hereby declare that the following is a full, clear, and exact description of the construction and operation of the same, reference being had to the annexed drawings, and to the letters of reference marked thereon, making a part of this specification.

A represents a shell or hollow body of metal, at one end of which is inserted a nut, and at the opposite end is arranged one or more slots or receptacles for the cutters, also a cap for retaining the cutters in position. B represents a piston, arranged with a screw fitted to the nut in the shell A, also arranged with one or more bevels, conforming to the cutters C C C for extending the radius of the cutters. C C C represent one or more movable cutters, arranged to conform to the formation of the spring D D and piston B, and operated by the ingress and egress motion of the piston. D D represent one or more springs, for the purpose of retaining the cutters in position to the piston. E represents a check-nut, fitted to the screw on the piston for the purpose of retaining the piston in a fixed position while operating the reamer.

What I claim as my invention, and desire to secure by Letters Patent, is—

The combination of the shell A, piston B, cutters C, and springs D, all constructed and arranged substantially as and for the purpose set forth.

WILLIAM F. PATTERSON.
